CONTINUOUS COMBUSTION TYPE ROTATING COMBUSTION
PRODUCTS GENERATOR AND TURBINE

Filed May 12, 1947

UNITED STATES PATENT OFFICE

2,612,021

CONTINUOUS COMBUSTION TYPE ROTATING COMBUSTION PRODUCTS GENERATOR AND TURBINE

Arthur Attwood Zuhn, Peoria County, Ill.

Application May 12, 1947, Serial No. 747,370

1. Claim. (Cl. 60—39.34)

1. My invention relates to a device for producing power from burning fuels by reaction of combustion gases. It is primarily intended for use in aircraft propellers and helicopter rotors. The device is lighter and has fewer working parts than the conventional internal combustion engines.

An exemplification of my invention is set forth in the accompanying drawing, wherein—

Figure 1 is a front view and partial section taken from line 1—1 Fig. 2 through a typical embodiment of the invention;

Fig. 2 is a side view and partial section from line 2—2 Fig. 1;

Fig. 3 is a sectional view taken from line 3—3 Fig. 2 through one of the blades;

Fig. 4 is a sectional view taken from line 4—4 Fig. 1 through a set of compressor blades; and

Fig. 5 shows an oblique view of the parts relative to the fuel-air mixing chamber.

The accompanying drawing exemplifies the invention as a pusher type aircraft propeller; however, this does not restrict its use, but is for convenience in illustrating the various features. Similar numerals refer to similar parts throughout the several views.

With reference to the drawing, my invention comprises, in general, a suitable mounting 6, an air compressor comprised of stationary blades 7 and revolving blades 8, a fuel supply line 20, a fuel nozzle or orifices 9, a number of valves 10, an annular shaped combustion chamber 11, a number of exhaust ducts 12, a means of ignition 13, a number of auxiliary air valves 15, a number of nozzles 16, a number of auxiliary air ducts having exteriors in the shape of a suitable airfoil 17, and a suitable bearing 18.

Air is taken into a number of stationary blades 7. Air leaving this set of blades is divided by a circular shaped wall 42 into two parts. One part flows around, adjacent to, and cools the chamber 11; and the other through a number of rotating blades 8 and then to the chamber valves 10.

Fuel is fed from the supply line 20 through a number of nozzles or orifices 9 into and mixed with the air going to the chamber valves 10. Mixing is accomplished by the revolution of the wall 42, chamber 11, and last set of revolving blades while the fuel nozzles or orifices are stationary.

The cylindrical wall 42 is attached to the blades 8 and at the rear to combustion chamber 11. The forward part of the wall 42 is separated by a gap from the rear part and is held by the rotating blades 8. Rotating blades 8 are attached

2 to the combustion chamber 11. This forms the mixing chamber 14 in which the fuel from the nozzles 9 and a portion of the air from the compressor mix to form an explosive mixture. The nozzles 9 and the fuel inlet tube 20 are assembled through holes in the hollow mounting 6 with the stationary nozzles 9 extending through the above mentioned gap in the rotating wall 42.

The combustion chamber valves 10 are pivoted near their hub edges and so proportioned to have a natural frequency of oscillation which is in the proper relation to the natural frequency of the gases in the exhaust tube 12 and the chamber 11. This permits proper opening and closing timing in relation to the pressure rise and fall in the exhaust tube 12 and chamber 11.

The air and fuel mixture is drawn into the chamber 11 and exhaust tube 12 through the chamber valves 10 by the differential in pressure caused by the reduced pressure in the chamber 11 and the increased pressure of the mixture. The reduced pressure in the chamber 11 is caused by the inertia effect of the gases leaving the nozzles 16 from the previous explosion.

25 The annular shaped combustion chamber 11 forms a common connection with the exhaust tubes 12. This provides equal reaction at the tips of the propeller blades by equalization of pressure. Since the reactions at the blade tips are equal, there is no force on the bearing 18 other than thrust.

The mixture is ignited by external means, a residual incandescent object, or a number of spark plugs 13.

35 The portion of air from stationary blades 7 which flows around the combustion chamber 11 and tubes 12 is heated by transfer through the walls of the chamber and tubes cooling them to workable temperatures. This air is then drawn through the auxiliary air valves 15 at a time when the inertia of the combustion chamber gases has lowered the pressure in the region of valves 15. The added mass of auxiliary air ahead of the explosion slug is accelerated and expelled 45 through nozzles 16 thus adding to the reaction. If auxiliary air valves are not provided a reverse flow takes place at tip nozzles 16 after the inertia of the gases has lowered the pressure at the tip nozzles. This reverse flow is detrimental to the production of tip reaction which drives the propeller.

50 The pendulum type pivoted valves are so proportioned to have a natural frequency that is a multiple of propeller speed. This makes possible the use of a simple timer in the ignition

system. The period of any pendulum is inversely proportional to the square root of the strength of the acceleration field. In the arrangement of my present invention the pendulum type valves, both combustion chamber inlet 10 and auxiliary air 15, are actuated by the combination of pressure variations and acceleration due to centrifugal effects. The strength of this acceleration is directly proportional to square of the propeller speed, therefore the resulting period of these valves is always inversely proportional to the propeller speed and is the same as the period of the ignition timer for all propeller speeds. The natural frequency of the gases in the system will be near that of the valves and ignition timer at operating speed.

The auxiliary air valves 15 are also so timed by having the correct frequency of oscillation to be closing or closed at the time the initial pressure wave reaches them. These auxiliary air valves 15 are pivoted near their hub edges and so proportioned to have a natural frequency which is in proper relation to the natural frequency of the gases in the combustion tube 12 and chamber 11, as in the case of the chamber valves 10. The products of combustion and air are prevented from flowing toward the center of the propeller by valves 10 and 15. The rapid rise in pressure resulting from the explosions in the tube 12 and chamber 11 cause the gases to flow through the nozzles 16 to the atmosphere at a rapid rate. This rapid increase in velocity of the gases produces a force reaction at the tips of the blades which revolves the propeller. Revolution of the propeller airfoils causes a thrust on bearing 18. This thrust is transmitted to the aircraft by a suitable mounting 6.

The rapid expansion of the gases in the exhaust tubes 12 and chamber 11 causes a lowering of pressure therein until a differential in pressure exists across the valves 10 and 15. The valves are so timed to swing open when this condition exists. The outer end of the exhaust tube 12 is then refilled with auxiliary air which has flowed around, adjacent to, and cooled the exhaust tube 12 and chamber 11; while the inner end of the exhaust tube 12 and chamber 11 are refilled with an explosive mixture of air and fuel. The entire cycle is then continuously repeated.

Although I have described my invention with a certain degree of particularity, it is understood

that the present disclosure has been made only by the way of example and that numerous changes in details of construction and the combination and arrangement of parts may be resorted to without departing from the spirit and scope of the invention hereinafter claimed.

What is claimed is:

A reaction motor comprising, in combination, a bearing, a mounting supporting said bearing, a fuel inlet tube, one or more fuel nozzles or orifices receiving fuel from said tube, an air compressor delivering a part of its air to a mixing chamber which also receives fuel from said nozzles, one or more pendulum type centrifugally motivated valves to control the flow of the air-fuel mixture into an annular shaped combustion chamber, an igniter for exploding the air-fuel mixture in said chamber, a number of exhaust tubes connected to said annular combustion chamber, a number of pendulum type centrifugally motivated auxiliary air valves which control the flow of a portion of the air from the stationary blades of the compressor to the exhaust tubes, and a nozzle at the outer end of each exhaust tube.
